Geo. P. Kimmel. ATTORNEY.

UNITED STATES PATENT OFFICE.

FREDERICK DOUGLAS COPPOCK, OF GREENVILLE, OHIO.

SLAB FOR RAILWAY CROSSINGS.

Application filed August 14, 1925. Serial No. 50,292.

To all whom it may concern:

Be it known that I, FREDERICK DOUGLAS COPPOCK, a citizen of the United States, residing at Greenville, in the county of Darke and State of Ohio, have invented certain new and useful Improvements in Slabs for Railway Crossings, of which the following is a specification.

This invention relates to a slab designed primarily for railway crossings, but it is to be understood that a slab, in accordance with this invention, can be employed for any purposes for which it is found applicable, and the invention has for its object to provide, in a manner as hereinafter referred to, a slab having both of its faces uniform to expedite the laying thereof, as well as to permit of the reversal of the slab when occasion requires, and further having its ends as well as its sides, uniform to enable the positioning of the slab from either end or side.

A further object of the invention is to provide, in a manner as hereinafter set forth, an armored slab having each of its faces reinforced at the marginal portion thereof throughout to increase the life of the slab and to take the wear.

A further object of the invention is to provide, in a manner as hereinafter set forth, a slab having armored sides and ends, and a wear take means on each of its faces whereby the strength and durability of the slab is materially enhanced.

Further objects of the invention are to provide, in a manner as hereinafter set forth, a reinforced composite slab for the purpose aforesaid, and which is simple in its construction, strong, durable, of standard form, thoroughly efficient in use, conveniently installed, and inexpensive to manufacture.

With the foregoing and other objects in view the invention consists of the novel construction, combination and arrangement of parts as hereinafter more specifically described, and illustrated in the accompanying drawings wherein is shown an embodiment of the invention, but it is to be understood that changes, variations and modifications can be resorted to which fall within the scope of the claims herewith.

In the drawings wherein like reference

characters denote corresponding parts throughout the several views:—

Figure 1 is a plan view of a composite slab in accordance with this invention.

Figure 2 is a longitudinal sectional view thereof.

Figure 3 is a transverse section.

Figure 4 is a plan view of the combined armor and reinforcing element.

Figure 5 is a longitudinal section, Figure 6 a transverse section and Figure 7 a fragmentary view in sectional elevation of said element.

Figure 8 is a top plan view of a railway crossing constructed with slabs in accordance with this invention.

Figure 9 is a section on line 9—9 of Figure 8.

Figure 10 is a section on line 10—10 of Figure 8.

Figure 11 is a fragmentary view, in plan, of a modified form of crossing.

Referring to Figures 1 to 6 of the drawings, the slab, in accordance with this invention, comprises a combined armor and reinforcing element and a body portion formed from plastic material preferably cement. The element aforesaid further functions as a mold or shaping element for the body portion.

The combined armor and reinforcing element, is of any suitable shape, preferably rectangular, of the desired width, height and length, and of standard dimensions as five inches in height, six feet in length and sixteen and one-half inches in width.

Both faces of the slab are uniform so the latter can be reversed or set upon either face, and this arrangement also applies to the ends and sides. The element includes a frame constructed of metallic material of the desired thickness and comprises a pair of side walls 1, 2 and a pair of end walls 3, 4. Each of said walls has its edges of greater thickness than the remaining portion thereof, and which is formed by an inclined offset on the inner face of each wall at the top and bottom thereof. The offsets of each wall are oppositely disposed with respect to each other and each gradually increases in thickness from its inner end toward its outer end. Each offset extends lengthwise throughout with respect to its wall and the

offsets of the side walls terminate in the offsets of the end walls. Each of said offsets is of a height materially less than half the height of its respective wall. The offsets not only increase the width of the edges of the walls for the purpose to take the wear upon the exposed face of the slab, but further act as anchoring means for maintaining the body portion within the combined armor and reinforcing element.

The enlarged edges of the side and end walls are indicated respectively at 5, 6, and 7, 8. The offsets on the inner faces of the side and end walls are indicated respectively at 9, 10 and 11, 12.

Welded with the inner faces of the side walls 1, 2, are the ends of two superposed sets of transversely extending, spaced, cylindrical brace and reinforcing rods or bars. The rods of one set are indicated at 13 and those of the other at 14. Welded with the inner faces of the end walls, 3, 4, are the ends of two superposed sets of longitudinally extending, spaced, cylindrical brace and reinforcing rods and the rods of one of said sets are indicated at 15 and those of the other set at 16. The rods 15 and 16 seat on the rods 13, 14 respectively. The rods 13 and 15 are positioned between the longitudinal median and one side and the rods 14 and 16 are arranged between the longitudinal median and the other side of the frame. The ends of the several sets of rods are spaced from the inner termini of the offsets on the inner faces of the walls of the frame.

The body portion of the slab is indicated at 17, is formed of a suitable plastic material, such as cement, and is poured into the frame, envelopes the reinforcing rods and is of such quantity to be flush with the enlarged edges of the said side and end walls. The material abuts against the inner faces of said walls and is overlapped by said offset portions, see Figures 2 and 3, whereby after the material hardens the body portion is anchored throughout at the top and bottom of its sides and ends, under which conditions a separation of the frame and body portion is prevented.

Referring to Figures 8, 9 and 10, a railway crossing is set up including a series of slabs, in accordance with this invention. The slabs are arranged in courses and are indicated 18, the track rails at 19, 20, wedge members between an opposed pair of the courses of the slabs at 21, filler elements between a pair of the courses of the slabs and track rails at 22, 23, supporting shims at 24, a filler between the pair of opposed slab courses at 25, and a concrete retaining means at each end of the courses, at 26. The crossing extends at an angle with respect to the track rails. The wedges are of wood and the filler between them is bitumen. The filler elements and the shims are of wood.

The height of the courses is governed by the thickness of the shims upon which they are mounted. Owing to the inclination of the crossing, each course of slabs projects beyond an adjacent course. The courses are arranged between and exteriorly of the track rails. The wedges bind the courses arranged between the track rails together and also against the filler elements 22. The course exteriorly of the track rails is anchored in position by any suitable means.

The construction of crossing shown in Figure 11 is the same as that illustrated in Figure 8, with the exception that the ends of the courses of the slabs 27 are flush with each other.

What I claim is:—

1. A slab comprising a combined armor and reinforcing element including a metallic frame having arranged therein and connected therewith spaced reinforcing bars, and a body portion of non-metallic material completely filling and flush with the side and end edges of the frame, said body portion completely enveloping said rods. 90

2. A slab comprising a combined armor and reinforcing element including a metallic frame having arranged therein and connected therewith spaced reinforcing bars, and a body portion of non-metallic material completely filling and flush with the side and end edges of the frame, said body portion completely enveloping said rods, said frame provided with means on the inner face thereof for overlapping said body portion to anchor the latter within the frame. 100

3. A slab comprising a combined armor and reinforcing element including a metallic frame having arranged therein and connected therewith spaced reinforcing bars, and a body portion of non-metallic material completely filling and flush with the side and end edges of the frame, said body portion completely enveloping said rods, said frame provided with means on the inner face thereof for overlapping said body portion to anchor the latter within the frame, said means extending throughout the inner face of each of the walls of said frame at each lengthwise marginal portion thereof, the means on the marginal portions of each of said walls being oppositely disposed and further increasing the width of the edges of its respective wall, and said slab being reversible. 110

4. A slab comprising a combined armor and reinforcing element including a metallic frame having arranged therein and connected therewith spaced reinforcing rods, and a body portion of non-metallic material completely filling and flush with the side and end edges of the frame, said body portion completely enveloping said rods, said rods extending transversely and longitudinally of said frame. 125

5. A slab comprising a combined armor and reinforcing element including a metallic frame having arranged therein and connected therewith spaced reinforcing rods, and a body portion of non-metallic material completely filling and flush with the side and end edges of the frame, said body portion completely enveloping said rods, said frame provided with means on the inner face thereof for overlapping said body portion to anchor the latter within the frame, said rods extending transversely and longitudinally of said frame.

6. A slab comprising a combined armor and reinforcing element including a metallic frame having arranged therein and connected therewith spaced reinforcing rods, and a body portion of non-metallic material completely filling and flush with the side and end edges of the frame, said body portion completely enveloping said rods, said frame provided with means on the inner face thereof for overlapping said body portion to anchor the latter within the frame, said means extending throughout the inner face of each of the walls of said frame at each lengthwise marginal portion thereof, the means on the marginal portions of each of said walls being oppositely disposed and further increasing the width of the edges of its respective wall, said rods extending transversely and longitudinally of said frame, and said slab being reversible.

7. A slab comprising a non-metallic body portion, and a metallic frame completely enclosing the sides and ends of said body portion, said frame having its edges flush with the exposed faces of said body portion and provided on its inner face with oppositely disposed inclined offsets overlapping the body portion for anchoring it within the frame, said offsets increasing the width

of the edges of the frame, and said slab being reversible.

8. A slab comprising a non-metallic body portion, a metallic frame completely enclosing the sides and ends of said body portion, said frame having its edges flush with the exposed faces of said body portion and provided on its inner face with oppositely disposed inclined offsets overlapping the body portion for anchoring it within the frame, said offsets increasing the width of the edges of the frame, and superposed sets of longitudinally and transversely extending reinforcing rods enveloped by said body portion.

9. A railway crossing comprising a plurality of courses of exteriorly armored and interiorly reinforced slabs arranged within and exteriorly of a pair of track rails, spaced wedges interposed between a pair of opposed courses arranged between the rails, filler elements positioned between the track rails and certain of the courses arranged between said rails, filler elements positioned between the courses exteriorly of the track rails and these latter, and filler means between said wedges.

10. A railway crossing comprising a plurality of courses of exteriorly armored and interiorly reinforced slabs arranged within and exteriorly of a pair of track rails, spaced wedges interposed between a pair of opposed courses arranged between the rails, filler elements positioned between the track rails and certain of the courses arranged between said rails, filler elements positioned between the courses exteriorly of the track rails and these latter, filler means between said wedges, and shims for supporting said courses at the desired height.

In testimony whereof, I affix my signature hereto.

FREDERICK D. COPPOCK.
